UNITED STATES PATENT OFFICE.

GEORGE P. COMEY, OF CLEVELAND, OHIO.

TWO-TONED RIMMED HAT.

1,096,827.

Specification of Letters Patent. Patented May 19, 1914.
Application filed February 9, 1910. Serial No. 542,931.

To all whom it may concern:

Be it known that I, GEORGE P. COMEY, a citizen of the United States, residing at Cleveland, in the county of Cuyahoga and State of Ohio, have invented certain new and useful Improvements in Two-Toned Rimmed Hats, of which the following is a specification.

In the millinery industry there are hats which are termed two-toned rim hats wherein the upper surface of the rim is of one material and color and the under surface is of another material, and preferably of another color, the two pieces of material being secured together and forming the two-toned rim referred to, and in the manufacture of these hats, it is customary to apply a wire stiffener to the edge and to roll the under covering, which is usually of velvet, over this wire and to hold such covering in place by the use of glue or some other similar material. This is particularly true of the French two-toned rimmed hat, where the velvet is usually extended beyond the hat rim, and the stiffener of wire, and is worked over onto the upper side around the wire and fastened thereto by glue or some other similar material so that a round bead is produced on the upper side and adjacent to the edge of the hat rim. A rim finished in this way presents a very neat appearance but it requires considerable time to bind the edge in this manner, and moreover the edge is very frail and becomes loose in places so that it must again be fastened down so that great care must be taken in handling the hat in order to avoid this loosening of the binding.

The present invention, therefore, relates to a hat having the edge of its rim bound in a manner such that it presents as neat an appearance as does the French hat, and further to the art of binding the rim of this type of hat, whereby it is rendered durable and practical so far as utility is concerned.

In conducting the method and producing the finished article, the formed hat, which is usually of straw, is provided with a facing for the underside of the rim consisting preferably of a stiffening layer of fabric such as buckram having secured to it the material which forms the lower facing. In the present instance this facing is velvet. Both of these thicknesses are shaped to conform to the configuration of

the underside of the rim of the hat. After trimming the edges of these two layers, the stiffener of buckram and the facing of velvet, so as to correspond to the configuration of the edge of the rim, a narrow bias binding corresponding to the facing is secured face to face along the edge of the facing of velvet by a row of stitching which passes through all the thicknesses at this point. An edge stiffener is then applied to these three layers for the purpose of holding the edge in place. This edge stiffener is of wire or any other suitable material and is secured in place in the usual manner by the use of a sewing machine designed for that purpose. After this has been accomplished, then the bias binding is turned over the wire stiffener and back upon the upper face of the rim stiffener of buckram, when the entire under facing is ready to be applied to the rim of the hat, and this is accomplished by placing the hat rim upon the buckram so that it laps over onto the edge of the binding which, as stated, has been doubled back onto the upper face of the rim stiffener and a row of stitching is applied through the rim of the hat, through the binding, through the rim stiffener of buckram, and through the under facing, and close up to the edge of the bias binding where it doubles back from the under facing. In order that this row of stitching shall be close to this edge, I employ a form of presser foot, for the sewing machine, having a groove on the underside thereof adjacent to and along one side of the needle from front to back and arranged to hold the bead formed by the binding, as it laps over the under facing, upright and away from the surface of the under facing so that the needle may pass close beside it and place the row of stitching close up to its edge, whereby when the hat is removed from the machine the flattening out of the bead formed on the under facing of the rim, together with the nap of velvet, if such a facing is used, will entirely hide the row of stitching. Usually the thread used for this stitching is of a different color from the under facing and corresponds in tone to the color of the rim of the hat so that it must be hidden.

The invention still further relates to certain details of construction of the article and to the art of producing the same as will be more clearly set forth in the accompanying specification, claim and drawings.

Referring to the drawings, Figure 1 shows a hat provided with the bead on the under-side of the rim; Fig. 2 shows portions of the rim stiffener of buckram or other similar material, the under facing which is preferably of velvet and the binding which is of velvet, all secured together by a row of stitching near the edge thereof; Fig. 3 is a similar view with the edge stiffener of wire or other similar material secured thereto; Fig. 4 shows the binding turned over the edge stiffener and with the hat rim in place; Fig. 5 represents the several parts in the position shown in Fig. 4 with the bottom side upward so that the bead engages in the groove formed on the underside of the presser foot; and Fig. 6 shows portions of the complete article with the bead hiding the row of stitching which secures the hat rim to the rim stiffener and facing.

In producing the finished article, the configuration of the rim 1 is transferred or duplicated in a well known manner on a sheet of stiffening material 2 such as buckram which forms a stiffener for the rim and which I will hereinafter refer to as the rim stiffener. It also forms a backing for the under facing 3 which is usually of velvet and which is secured to the stiffener 2 in any suitable manner. The rim stiffener 2 as well as the facing 3 are applied to the hat rim and cut sufficiently so that they conform to the edge of the rim of the hat. A bias binding 4, preferably of velvet and corresponding in shade to the facing 3 is then secured with its face toward the face of the facing and to the rim stiffener 2 by means of a row of stitching 5 which is preferably as close to the edge of the parts as is practical. An edge stiffener 6 of wire, or other suitable material, is then sewed by stitches 7 to the edge of the parts 2, 3 and 4 as is shown in Fig. 3 and the binding 4 is turned over this

edge stiffener and back onto the upper face of the rim stiffener 2 as is shown in Fig. 4. 45 When the binding 4 is of bias material it will turn back nicely in the manner just described and the edge will be extremely neat.

The next step is the sewing of the rim of the hat to the rim of the parts just described, 50 and this is accomplished by a row of stitching 8 passing through the several thicknesses of the under facing and of the rim and close to the edge of the binding where it is folded back from the under facing. 55

In bringing about the location of the stitching 8 close to the edge of the binding, a presser foot 9 is employed having a groove 10 from front to back adjacent to the needle opening 11 whereby the wall of the groove 60 will hold the edge of the bead close to, but out of the way of, the point of the needle, thus permitting the stitches to be formed close to this edge. After these stitches are formed the binding will spread out over the 65 stitching and hide it from view so that ordinarily it would appear as though there was no stitching at this point as is shown in Fig. 6.

Having described my invention, I claim:— 70

A hat comprising a crown, a straw rim, and an under facing consisting of a layer of stiffening, a facing layer of fabric, and a binding of fabric first secured by a row of stitching against the facing layer and near the outer edge thereof and then doubled over the same forming a finishing bead at the edge, said entire facing being secured to the rim of the hat by means of a row of stitching. 75

In testimony whereof I affix my signature in presence of two witnesses as follows:

GEORGE P. COMEY.
